UNITED STATES PATENT OFFICE

139,560

DESIGN FOR A BEVERAGE SERVING TRAY

William L. Wentling, Euclid, Ohio

Application August 22, 1944, Serial No. 114,971

Term of patent 7 years

(Cl. D44—10)

To all whom it may concern:

Be it known that I, William L. Wentling, a citizen of the United States, residing at Euclid, county of Cuyahoga, and State of Ohio, have invented a new, original, and ornamental Design for a Beverage Serving Tray, of which the following is a specification, reference being had to the accompanying drawing, forming a part thereof.

Fig. 1 is a front elevational view of a beverage serving tray showing my new design when supported in a vertical position;

Fig. 2 is a view in side elevation of the tray shown in Fig. 1;

Fig. 3 is a bottom plan view of the tray;

Fig. 4 is a top plan view of the tray in a horizontal position; and

Fig. 5 is a view in end elevation of the tray when disposed in a horizontal position.

I claim:

The ornamental design for a beverage serving tray, substantially as shown.

WILLIAM L. WENTLING.
